(57) **CLAIM**

The ornamental design of a math game or portion thereof, substantially as shown and described herein.

DESCRIPTION

FIG. 1 is a perspective view of a math game in accordance with the present design.

FIG. 2 is a left side view of the math game of FIG. 1, of which the right side view is a mirror image thereof.

FIG. 3 is a rear view of the math game of FIG. 1.

FIG. 4 is a front view of the math game of FIG. 1.

FIG. 5 is a top view of the math game of FIG. 1.

FIG. 6 is a bottom view of the math game of FIG. 1.

FIG. 7 is a perspective view of the math game according to a second embodiment.

FIG. 8 is a left side view of the math game of FIG. 7, of which the right side view is a mirror image thereof.

FIG. 9 is a rear view of the math game of FIG. 7.

FIG. 10 is a front view of the math game of FIG. 7.

FIG. 11 is a top view of the math game of FIG. 7; and,

FIG. 12 is a bottom view of the math game of FIG. 7.

The broken line elements shown illustratively in FIGS. 1, 2, 3, 7, 8 and 9, depict exemplary components which might be used in conjunction with the math game and form no part of the design claim.

The game can be played with a projectile, such as a ball, a beanbag, a shuffleboard puck, a hockey puck, a rock, a shuttlecock, or the like.
